UNITED STATES PATENT OFFICE.

FREDERIC J. PLONDKE, OF ST. PAUL, MINNESOTA.

OPERATING BED.

Application filed January 27, 1922. Serial No. 532,219.

To all whom it may concern:

Be it known that I, FREDERIC J. PLONDKE, a citizen of the United States, and a resident of St. Paul, in the county of Ramsey 5 and State of Minnesota, have invented certain new and useful Improvements in an Operating Bed, of which the following is a specification.

One object of my invention is to provide 10 a bed of such construction that it can not only be efficiently used for an operating table, but will also at other times present a neat and attractive appearance in the patient's room.

15 An incidental object is to provide improved means for removing the head and foot of the bed when an operation is to be performed.

Another object is to provide improved 20 means for narrowing the bed so the surgeon may work to better advantage on the patient lying on the bed.

With these and incidental objects in view, 25 the invention consists of certain novel features of construction and combination of parts, the essential elements of which are hereinafter described with reference to the drawings which accompany and form a part of this specification.

30 In the drawing, Figure 1 is a perspective view of my improved bed as it would ordinarily appear in a patient's room. Figure 2 is a similar view but with the head, foot and one-half of the bed lowered, so as to 35 bring it into position for an operation on the patient occupying the bed. Figure 3 is a perspective view of the bed in its operating position with a mattress carried by the springs and showing the manner in which 40 the mattress folds down out of the surgeon's way. Figure 4 is a section taken on the line 4-4, Figure 1. Figure 5 is a section taken on the line 5-5, Figure 4. Figure 6 is an 45 enlarged detail of one of the head posts of the bed, and Figure 7 is a view taken at right angles to that shown in Figure 6.

The bed consists essentially of a head 1 and foot 2 connected by a fixed rail 3, a centrally supported rail 4 and a detachable 50 rail 5, which carry thereon the spring frame 6 which is hinged near the center thereof at 7.

The removable rail 5 has an aperture 8 at each end thereof fitted over dowels 9 55 carried by the head and foot members 1 and 2 as shown in Figures 1 and 4.

When this rail is removed the spring frame drops down in the manner clearly shown in Figure 2, thereby transforming the bed as shown in Figure 1 into a narrow operating table as shown in Figure 2.

60 The head and foot members are of similar construction and each comprises a lower rigid portion having the two posts 9 and 10 suitably connected by pipes or rods 11 and 12 and angle header 13 which supports one end of the bed spring frame.

65 The lower ends of the posts 9 and 10 have slidably mounted therein rods 14 and 15 respectively mounted on anti-friction rollers 16 and 17, pins 18 passing through apertures in posts 9 and 10 and rods 14 and 15, provide means for raising or lowering the bed.

70 The upper ends of the posts are hollow 75 as is better shown in Figures 6 and 7 and are adapted to receive plugs 19, Figures 6 and 2, in a snug fit so the upper portions 20 and 21 of the head and foot respectively 80 may be similarly mounted in their respective lower portions.

85 Each of the plugs 19 has hinged thereto a link 22 which in turn has hinged thereto a loop 23, the opposite end of which encircles the pin 24 passing through the post.

90 It will be apparent that with this construction when the bed is in the position shown in Figure 1 the head or foot may be lifted up so the plugs 19 are drawn clear of their respective posts and then swung 95 downwardly into the position shown in Figure 2.

95 The bed is preferably provided with a mattress such as 25, Figure 3, and hooks 26 are provided to engage in apertures 27 so the mattress will not spread at its hinge line when it is flat on the bed.

100 It is apparent that with this construction and with the mattress hooked together, a bed is provided that will be not only comfortable in every respect for the patient, but will also be slightly in appearance, and yet in case a patient is in a condition where it would be dangerous to move him to the operating room, the bed may be quickly 105 changed into an operating table of such size and shape and have such adjustments for height that the surgeon in charge may perform the necessary operation with practically as much ease and precision as if the patient were in the operating room and on an operating table.

2
While I have described my invention and illustrated it in one particular design, I do not wish it understood that I limit myself to this construction, as it is evident that the application of the invention may be varied in many ways within the scope of the following claim:

In a hospital bed the combination of a lower foot panel having two vertical posts,

an upper foot panel having two vertical posts each terminating in a plug adapted to fit in an aperture in the posts of said lower foot panel, links hinged to each of said plugs, loops hinged to each of said links the lower ends of said loops encircling pins passing through the hollow upper ends of the posts of said lower panel.

FREDERIC J. PLONDKE.
